UNITED STATES PATENT OFFICE.

EDWARD McCLURE, OF CHICAGO, ILLINOIS.

WIRE-MESH GUARD AND THE LIKE.

Application filed May 22, 1925. Serial No. 32,116.

This invention relates to wire mesh guards, panels and the like, and one of its objects is to reduce to a minimum the amount of time and labor required to manufacture the article. Another object is to provide a strong, substantial and rugged connection between the wire mesh work of guards and the border frame which surrounds it. The common practice of securing the border frame to wire mesh work, is to form holes in a channel or other bar, insert the ends of the wires through the holes and bend them back against the bar. This is a tedious and irksome task and requires much time and at the present price of labor the cost of production is an important item. In accordance with the present invention, a great deal of the time and labor is saved, and a better and more effective connection is made between the wire mesh work and the border frame. The invention consists in the several novel features of construction and arrangement as will fully appear in the following specification, and the essential features of which will be more definitely pointed out in the appended claims.

The invention is clearly illustrated in the accompanying drawing, in which:—

Fig. 1 is a perspective view of a fragment 30 of a wire mesh guard embodying one form of the present invention; Fig. 2 is a detail, vertical, cross section thereof; Fig. 3 is a horizontal section partly broken out and taken on the line 3—3 of Fig. 1; Fig. 4 is a side elevation, partly broken out, of a fragment of a wire mesh guard showing a slightly modified form of the invention; Fig. 5 is a detail, horizontal section taken on the line 5—5 of Fig. 4; Fig. 6 is a detail, vertical, cross section through a second modified form of the invention and Fig. 7 is a detail, vertical, cross section of another modified form.

Referring to said drawing, and first to Figs. 1 and 3 inclusive, which illustrate the preferred embodiment of the invention, the reference character 8 designates a fragment 45 of a panel of wire mesh work which may be square, rectangular, or of any other desired shape. The wire mesh work shown is of the "square mesh" type, formed of interwoven wires 9, 10, that extend at right angles to each other, and at right angles to the members of the border frame.

A fragment of the border frame is seen 50 at 11 and, as is well understood, said frame

surrounds the wire mesh work. In its preferred form the border frame member 11 comprises two oppositely disposed channel bars 12, which are set with their flanges edge 60 to edge as is clearly seen in Fig. 2, and secured together by bolts, rivets or the like 13. In the edges of the flanges 14 of the channel bars, notches 15, 16 are formed, the notches in each flange being made equidistant, there being one notch for each alternate wire, and those in one flange being disposed midway between those in the other flange. The shape of the notches is immaterial except that they are of sufficient size 70 to receive a wire 9 or 10. When the parts are assembled the plain edge portions of one flange 14 close the notches opposite it, thereby providing closed holes through which the wires of the wire mesh work extend into the 75 channel formed by the two channel bars.

As is well understood, the wires of wire mesh work are kinked as is best shown in Fig. 2, the kinks of the alternate wires being aligned and those of the intermediate wires 80 being also in alignment at places midway between the kinks of the other wires. The wires extend through the holes of the border frame members at the kinked places of the wires, and an end wire 9^x of the wire mesh 85 work may be contained in the channel, formed by the two opposing channel bars. When bolted or otherwise secured together, the two channel bars are positively secured upon the wire mesh work and the latter is 90 disposed along the medium line of the border frame.

In assembling the parts, an edge portion of the wire mesh work is laid upon one of the channel bars with the aligned crimps 95 of the alternate wires contained in the notches. The opposite channel bar is then placed upon said channel bar with the notches thereof receiving the intermediate wires, after which the two channel bars are 100 bolted or riveted together. The other edges of the wire mesh are connected with the border frame members in the same manner. If desired, the four channel bars of each side may be welded together at the corners 105 or secured together in any other desired manner to form a rectangular frame, and when the wire mesh work and frames have been assembled, the opposite bars of the frames may be bolted, riveted or otherwise 110 secured together.

Figs. 4 and 5 illustrate the application of

- the invention to diamond mesh work 8^a, and in this case the notches 15^a, 16^a are provided in the flanges 14^a of the channel bars 12^a, at the places where the wires 9^a, 10^a of the wire mesh work intersect each other adjacent the edge portion thereof. In this case the notches in each flange are located opposite each other, and the two opposing notches receive two intersecting wires of the wire mesh work.
- 10 It may be observed that the same spacing of notches may be had for the wire mesh work shown in Fig. 4 as the wire mesh work shown in Fig. 1, but instead of forming the notches in one bar for the alternate wires, 15 and the notches in the other bar for the intermediate ones, the notches of each channel bar are placed opposite those of the other and receive the intersecting wires of the wire mesh work.
- 15 In Fig. 6 one notched channel bar 12^b is shown for receiving the ends of the wire mesh work 8^b, and a flat unnotched bar 12^c cooperates therewith to hold the wires in the channel. The channel bar and flat bar 20 may be secured together by bolts or rivets as in the other forms.
- 20 In Fig. 7 two oppositely disposed angle iron bars 12^d are shown, one having the notches for receiving the wire mesh work 8^a.
- 30 The two angle iron bars are placed together as shown, thereby forming a channel in which the end portion of the wire mesh is received. The two angle irons may be bolted or riveted together as in the other forms.
- 35 From the above it is evident that all of the labor of inserting the ends of the wire mesh through holes in the bars is eliminated and also the work of bending the wires back after they have been so inserted. The parts 40 may be assembled with a minimum amount of time and labor and when assembled, the parts provide a wire mesh guard which is handsome and attractive in appearance and one which is substantial, strong and rigid.
- 45 More or less variation of the exact details of construction is possible without departing from the spirit of this invention; I desire, therefore, not to limit myself to the exact form of the construction shown and de- 50 scribed, but intend, in the following claims, to point out all of the invention disclosed herein.
- 55 I claim as new, and desire to secure by Letters Patent:
1. A wire mesh guard, comprising wire mesh work formed of interwoven crimped wires, a border frame member secured upon the edge of the wire mesh work and com-
- posed of two laterally separable contacting bars, at least one of which is formed with 60 a flange having spaced notches therein for receiving intersecting end portions of crimped wires which form the wire mesh work, an edge portion of the other bar closing said notches around the crimped wires, 65 with intersecting end portions of the crimped wires contained between said bars, and connecting means for securing said bars together with the crimped intersecting end portions 70 of the wires of the wire mesh work contained in the notches of one bar.
2. A wire mesh guard, comprising wire mesh work formed of interwoven crimped wires, a border frame member composed of two oppositely disposed laterally separable contacting flanged bars, each formed with notches in one of its flanges for the reception of end portions of crimped wires which form the wire mesh work, an edge portion of each 75 bar closing the notches around the crimped wires, and means for securing said bars together with the crimped end portions of the wires of the wire mesh work contained 80 in the notches of the bars.
3. A wire mesh guard, comprising wire mesh work formed of interwoven crimped wires, a border frame member formed of two oppositely disposed laterally separable, flanged bars, each formed with notches in 85 one of its flanges for the reception of end portions of the crimped wires which form the wire mesh work, the notches in one flanged bar being arranged intermediate the notches of the other flanged bar, and an edge portion of each bar closing the notches 90 around the wires, and means for securing said bars together with the crimped end portions 95 of the wires of the wire mesh work contained in the notches of said bars.
4. A wire mesh guard, comprising wire mesh work formed of crimped, interwoven wires, a border frame member formed of two oppositely disposed laterally separable channel bars set with their flanges edge to edge and each channel bar being formed with 100 notches in one of its flanges for the reception of crimped end portions of the wires which form the wire mesh work, the notches in one channel bar being arranged intermediate the notches of the other channel bar, and an edge portion of each bar closing the notches 105 around the wires, and means extending through said bars for securing them together upon the wire mesh work.

EDWARD McCLURE.
